UNITED STATES PATENT OFFICE.

WILLIAM THOMAS BUCKINGHAM ROBERTS, OF LEICESTER, ENGLAND, ASSIGNOR TO
OSWALD VERNON FORBES, OF LONDON, ENGLAND.

MACHINE FOR TRIMMING THE HEELS OF BOOTS AND SHOES.

974,708.

Specification of Letters Patent.

Patented Nov. 1, 1910.

Application filed June 6, 1910. Serial No. 565,375.

To all whom it may concern:

Be it known that I, WILLIAM THOMAS BUCKINGHAM ROBERTS, a subject of the King of Great Britain and Ireland, residing at Leicester, England, have invented certain new and useful Improvements in Machines for Trimming the Heels of Boots and Shoes, of which the following is a specification, reference being had therein to the accompanying drawing.

This invention relates to machines performing the operations that are commonly known as trimming, or as trimming and breasting heels, before they are attached to boots or shoes.

Certain features of the invention are more particularly directed toward enabling the performance of the before mentioned operations separately on each of the parts that constitute a renewable heel, that is made in two parts, one of which is securely fastened to the shoe, and the other of which forms a renewable tread face.

Broadly speaking, the invention consists in a machine provided with means for positioning and clamping a heel in relation to a coöperating rotary cutter, in such a manner that without being unclamped, the heel may be trimmed all around its margin including its breast surface.

According to one feature of this invention, the clamping devices are constituted as two members adapted to engage the opposite faces respectively of the heel, or when the heel is made in two parts, each part may be held separately to be trimmed and breasted. In cases where the heel is partly renewable, the parts are each preferably positioned in the machine by a suitable clamping member formed to correspond with the shape of the inter-locking portion of the part of the heel to which it is allotted.

The clamping devices which engage the heel on either side are preferably interconnected together in such a manner as to rotate in unison, and are so arranged as to present the heel to a rotary cutter suitably formed for both trimming and breasting it.

A further feature of the invention consists in the provision of means for controlling the general contour to which the margin and breast of the heel is to be trimmed, and also the pitch or angle of the said margin when viewed laterally. Such controlling means preferably comprise two cams, one of

which corresponds to the contour of the heel, and the other to the pitch thereof. These cams are rotated in unison with the heel and work against suitable abutments, or rollers, and preferably are made in sets 60 interchangeable to suit different shapes of heels.

A specific construction of machine embodying these and other features of the present invention, and adapted, by way of example, for use in trimming and breasting a sectional or two part heel will now be described with reference to the accompanying drawings, in which:

Figure 1 is a plan of the machine. Fig. 70 2 a side elevation partially in section of the head of the machine. Fig. 3 an end elevation partially in section. Fig. 4 is a perspective view of a two part or sectional heel showing the manner of associating the parts 75 thereof.

According to the machine illustrated, each portion of the heel to be trimmed and breasted is, separately, held in a rotatable clamping device which presents each portion of 80 the margin of the heel part to a rotary cutter. The two members *a* *b* of the clamping device are carried in a bracket *f* which is mounted on a horizontal pivot *f*¹, so as to be capable of vibrating in a vertical plane. 85 The member *b* is furnished with a forming cam *d*, which bears against a roller *d*¹ mounted adjacent to a rotary cutter *c*. The periphery of the forming cam *d* corresponds to the periphery of the heel, and during the 90 rotation of the latter, together with the cam, the bracket *f* whereon these parts are mounted is so actuated about its pivot *f*¹ as to advance and retract the heel toward, and away from, the cutter *c* thereby trimming the 95 heel to the contour required for the margin and the breast thereof.

To vary the pitch or angle at which the heel is to be presented to the cutter, the clamp carrying bracket *f* is pivoted to another member *g*, arranged to turn about a vertical axis *g*¹ which intersects the periphery of the cutter *c* in a line with the position of the interlocking face of the heel part that is being trimmed.

Approximately coincident with the pivotal axis *f*¹ of the bracket *f*, is a counter-shaft *b*², which is driven from a shaft *b*⁴ of the clamping device, and which is provided with a suitably shaped cam *e* that bears 110

against a roller e^1 mounted upon the machine frame h . The cam e determines the angular position of the member g , and with it the angular motion of the clamp-carrying bracket f , and the heel, about the axis g^1 , that crosses the periphery of the cutter. The bracket f , may be controlled by a spring f^4 , so arranged as to maintain the cam d in engagement with the roller d^1 , or it may 10 be positively driven.

To secure the seat portion of the heel in the clamping device, a rod f^5 is provided which passes through the center of the shaft b^4 whereby the device is rotated. The inner extremity of the rod f^5 is screw threaded to enter the nut or barrel a , usually contained in the seat portion of the heel, while the opposite extremity of the rod is furnished with a knurled head f^6 for rotating 20 said rod.

The face b^2 of the member b is preferably formed with a dovetail x^1 , which corresponds to the inter-locking face of the seat portion and which acts as a positioning device for the heel. The shaft b^4 , which carries the clamping device, may be rotated by a hand-wheel b^6 , or by any other suitable means.

To secure the tread portion of the heel in 30 the clamp during trimming, the member a is mounted upon the inner end of a shaft a^1 , arranged co-axial with the shaft b^4 pertaining to the member b . The outer end of the shaft a^1 is screw threaded and works in a 35 nut a^4 , which serves to feed the member a forward to clamp the tread of the heel against the member b . The rod f^5 which passes through the shaft b^4 of the member b , is preferably screwed into the member a , 40 so as to secure the two members together.

Upon the outer extremity of the shaft a^1 , is mounted a gear wheel a^2 , which corresponds with a gear wheel b^7 mounted upon the outer extremity of the shaft b^4 pertaining 45 to the member b of the clamping device, and these wheels are inter-connected by means of gear wheels a^3 , b^8 , respectively mounted upon the opposite extremities of an idle shaft b^9 . This idle shaft is driven 50 by said gear wheels, and, in turn, drives the shaft b^3 , whereon is mounted the cam e for varying the pitch or angle at which the heel

is presented to the cutter. In this manner the cam turns in unison with the heel being trimmed.

In order to adjust the heel relatively to the cutter e , and thereby the amount of cut, the roller d^1 , against which the forming cam d bears, is mounted upon a slide d^2 , which is capable of being clamped, in its 60 adjusted position, by means of a knurled nut d^{10} , having a locking handle d^{11} , or by any other suitable means.

It is to be understood that various modifications may be made in the hereinbefore 65 described machine without departing from the spirit of the invention.

Having now described my invention, what I claim is—

1. A machine for trimming heels of boots 70 or shoes comprising a rotary cutter, clamping devices for holding the heel and provided with securing means for connecting said clamping devices and holding the heel thereto, the cutter and clamping devices 75 having relative motion, means for causing the clamping devices to present the heel to the cutter, and means for transferring the line of operation of the cutter all around the margin and also the breast of the heel.

2. A machine for trimming heels for boots or shoes comprising a rotary cutter, clamping means for holding the heel and provided with securing means for connecting said clamping means and holding the heel thereto, the cutter and clamping means having relative motion and the clamping means presenting the heel to the cutter, means for causing the cutter to trim all around the margin and the breast of the heel, two cams 85 automatically controlling the relative motion of the cutter and clamping means, one cam governing the margin and the other the breast of the heel, means for coupling the cams to move in unison with the clamping 90 means, and operating mechanism.

In witness whereof, I have hereunto signed my name in the presence of two subscribing witnesses.

WILLIAM THOMAS BUCKINGHAM ROBERTS.
